REDUCING LENS STAND

Cesar P. Da Corta, Wakefield, Mass.

Application October 26, 1950, Serial No. 12,739

Term of patent 14 years

(Cl. D57—5)

To all whom it may concern:

Be it known that I, Cesar P. Da Corta, a citizen of the United States, residing at Wakefield, in the county of Middlesex and Commonwealth of Massachusetts, have invented a new, original, and ornamental Design for a Reducing Lens Stand, of which the following is a specification, reference being had to the accompanying drawing forming a part thereof, in which:

The figure is a view in perspective of a reducing lens stand showing my new design.

I claim:

The ornamental design for a reducing lens stand substantially as shown.

CESAR P. DA CORTA.
